UNITED STATES PATENT OFFICE.

JOHN L. WHEELER, OF ST. LOUIS, MISSOURI, ASSIGNOR TO SIMPLEX SHOE MACHINERY COMPANY, OF ST. LOUIS, MISSOURI, A CORPORATION OF MISSOURI.

PRESSER-FOOT MECHANISM

1,189,893.

Specification of Letters Patent.

Patented July 4, 1916.

Application filed July 23, 1915. Serial No. 41,428.

To all whom it may concern:

Be it known that I, JOHN L. WHEELER, a citizen of the United States, residing in the city of St. Louis and State of Missouri, have invented new and useful Improvements in Presser-Foot Mechanisms, of which the following is a specification.

This invention relates to sewing machines, and more particularly to work-holding devices or presser-foot mechanisms for holding the work in a machine for sewing leather and similar heavy material.

The invention has for its objects to produce a simple and efficient mechanism for holding the work tight upon the supporting table while the awl is puncturing the work and the needle is carrying the stitching thread therethrough, and for releasing the pressure on the work during the feeding thereof; and, further, to provide for a neutral position of the parts of the mechanism, so that the work-clamping member or presser-foot may be manipulated by hand when placing the work in and removing it from the machine.

Other objects and advantages will appear from the following description.

In the drawings,—Figure 1 is a side elevation of a portion of a sewing machine illustrating an adaptation of the invention, the parts of the mechanism being in the positions they assume when the work is clamped on the supporting table; Fig. 2 is a fragmentary view, on an enlarged scale, showing the parts of the mechanism in the neutral position; Fig. 3 is a similar view showing the position of the parts when the presser-foot is mechanically raised to permit the feeding of the work; Fig. 4 is a view illustrating a modification of the invention; Fig. 5 is a view, partly in top plan and partly in horizontal section of the mechanism shown in Fig. 4; and Fig. 6 is a fragmentary detail view of the cam or tripper plates of the mechanism illustrated in Figs. 4 and 5.

Referring now to these drawings, the numeral 1 designates the bed-plate or base of the sewing machine, upon which a head-frame or standard 2 is mounted. At the front of the head-frame is a work-table or support 3 having a slot 4 therein for the passage of a curved awl 5 and an oppositely-disposed, similarly curved needle 6; said awl being arranged and adapted to perforate

the work, and the needle following the awl on its downward stroke to carry the stitching thread through the work; the awl being oscillated in one direction to feed the work before it has receded therefrom. This type 60 of machine is more fully described in Letters-Patent No. 1,016,898, granted to Savignac & Myers on February 6, 1912; and in an application Ser. No. 807,225, filed by Charles E. Myers and myself, on the 17th 65 day of December, 1913. Hence no further description of the machine in its entirety is deemed necessary in this specification. Furthermore, as far as the present invention is concerned, it may be applied to other types 70 of machines utilizing either curved or straight awls and needles.

Pivottally mounted on a stud 7 projecting from the side of the head-frame 2, as more clearly shown in Figs. 5 and 6, is a lever member 8. The forward portion 9 of this lever member is bent angularly, as at 10 (see Fig. 5), so as to overhang the work table 3, said portion 10 having a slot 11 therein for the passage of the awl and the needle. At 80 the rear end of the lever 8 is a sector 12 having on its peripheral face two oppositely-arranged sets of serrations or ratchet teeth 13, 14.

A spring 15 which constantly tends to 85 raise the lever member 8 so as to hold the presser-foot portion yieldingly on the work, is attached at one end to said lever member and at its opposite end, either to a stud 16 on the head-frame, as shown in Fig. 1, or 90 to a stud 17 on a crank-arm 18, which latter is mounted on a rotatable rod 19 extending through the head-frame and provided on its end with a handle 20 or other suitable device for rotating the rod. In the latter case 95 the crank-arm 17 may be thrown from the position shown by full lines in Fig. 4 to the position shown by dot and dash lines in said figure, in which latter position it rests against a stop 21 projecting from the side 100 of the head-frame. The object in thus attaching the spring 15, in some cases, is to provide a different tension for relatively thin and thick work. For thick work the presser-foot portion 9 of the lever 8 will obviously be raised higher than for thin work. Therefore, the crank arm 17 should be moved to the lower position shown by the full lines in Fig. 4; while for thin work said arm should be in the upper position.

Pivoted about the same axis as the lever 8 is an actuating lever 22. Preferably, as shown in Fig. 5, the lever 22 has a hub portion 23 which is journaled on a hub extension 24 of the lever member 8, both the lever 8 and the lever 22 being retained on the stud 7 by a cap screw 25. On the lever 22 are two oppositely-disposed ears 26 to which are attached pawls 27 and 28, which are oppositely-disposed and adapted to respectively engage the sector teeth 13 and 14, said pawls being connected by a spring 29 which serves to hold them in engagement with said sector teeth. The pawls may be provided 10 with a single tooth or engaging portion, as shown in Fig. 1, or, as is more preferable, they may be provided with a series of teeth which are counterparts of the teeth on the sector, as shown in Fig. 4.

As shown in Fig. 1, there may be provided a pair of studs 30 which are arranged so as to be engaged by the pawls 27 and 28, the arrangement being such that when the lever 22 is moved to a neutral position both 20 of the pawls will be out of engagement with the sector portion 12 of the lever 8, but when the lever is raised from said neutral position the pawl 27 will engage the toothed portion 13 of the sector, thereby tending to raise the rear portion of the lever 8 and depressing the presser-foot or work-clamping portion 9. On the other hand, when the lever is moved in the opposite direction from the neutral position the pawl 28 will engage the toothed portion 14 of the sector and act 30 to raise the presser-foot.

Instead of providing the studs 30 as shown in Figs. 1 to 3, the pawls 27 and 28 may be provided with inwardly-projecting 40 studs 31 (see Fig. 5), which are arranged and adapted to coöperate with cam-plates 32, said cam-plates having shouldered portions 33 which are positioned so as to be engaged by the studs 31 when the lever arm 22 is in neutral position, the action of the 45 pawls on the sector portion 12 of the lever 8 being the same as in the modification first described. The cam-plates 32 are segmental and they are preferably mounted in an arcuate slot or groove 34 on the head frame 2 so as to provide for adjustment concentric with 50 respect to the axis of the levers 8 and 22, such adjustment being readily effected by providing the plates with slots 35 through 55 which securing screws 36 are inserted into the head-frame.

The lever arm 22 may be operated through any suitable mechanism in timed relation to the operation of the awl and the needle, according to the structure of the machine as a 60 whole. For the purposes of illustration, however, a cam-slot 37 is provided in the actuating disk 38 which is provided on the power shaft 39 of the machine of the type referred to in the Letters-Patent and application hereinbefore mentioned. The lever arm 22 is provided with a roller 40 at its outer end which works in said cam-slot 37, the major portion of said slot being concentric with the axis of the shaft 39, and its 70 relative distance from said axis being such that the lever arm is raised while the roller is in the concentric portion of the slot, and the presser-foot is clamped upon the work. For a short portion of its length the cam-slot is indented or reentrant toward the axis of the shaft 39, as at 41, so that when the roller rides therein the lever arm 22 will be in neutral position. This is timed so that the neutral position is reached about the 75 time the awl and the needle are both clear of the work and the mechanism of the machine is in such condition that the work may be placed in and removed from the machine. Another indented portion 42 is provided in 80 the slot, which causes the end of the lever arm to move closer to the axis of the shaft 39 as the roller rides therein, whereby the lever arm is moved below its neutral position and effects the raising of the presser-foot during the time the work is being fed. or, as in the case of the machine illustrated and described in the Letters-Patent and application hereinbefore referred to, while the awl is being oscillated to feed the work. 95

For convenience in manipulating the presser-foot by hand when placing the work in, and removing it from, the machine, a handle 43 is provided on the lever member 8. This handle may be located either at a 100 point below the actuating lever 22, as shown in Figs. 1, 2 and 3, or above said actuating lever, as shown in Figs. 4 and 5, as may be preferred.

Obviously the device admits of considerable modification without departing from the spirit of the invention. Therefore I do not wish to be limited to the exact construction and arrangement shown. 105

I claim:

1. In a sewing machine, a work support, and means for holding the work on said support, said means comprising a lever having a forwardly-extending work-clamping portion and a rearwardly-extending sector portion, said sector having two oppositely-arranged sets of teeth, an actuating lever pivoted about the same axis as said first-mentioned lever, a pair of oppositely-disposed pawls on said actuating lever arranged and adapted to respectively engage a set of said teeth on the sector portion of said first-mentioned lever, means for operating said actuating lever to a neutral position and to positions on opposite sides of the neutral position, means coöperating with said pawls whereby they are both out of engagement with said sector portion of said first-mentioned lever in the neutral position of said actuating lever, and whereby said 110

115

120

125

130

5 pawls alternately engage said sector portion to move said first-mentioned lever in the corresponding direction when said actuating lever is moved from neutral position,
5 and a spring acting upon said first-mentioned lever to hold its work-clamping portion yieldably on the work.
10 2. In a sewing machine, a work support, and means for holding the work on said support, said means comprising a lever having a forwardly-extending work-clamping portion and a rearwardly-extending sector portion, said sector having two oppositely-arranged sets of teeth, an actuating lever pivoted about the same axis as said first-mentioned lever, a pair of oppositely-disposed pawls on said actuating lever arranged and adapted to respectively engage a set of said teeth on the sector portion of
15 said first-mentioned lever, means for operating said actuating lever to a neutral position and to positions on opposite sides of the neutral position, means coöoperating with said pawls whereby they are both out
20 of engagement with said sector portion of said first-mentioned lever in the neutral position of said actuating lever, and whereby said pawls alternately engage said sector portion to move said first-mentioned lever
25 in the corresponding direction when said actuating lever is moved from neutral position, and a spring acting upon said first-mentioned lever to hold its work-clamping portion yieldably on the work, the operating
30 means for said actuating lever being relatively arranged and adapted so that the motion transmitted to said first-mentioned lever is less in the direction to effect the
35 clamping of the work than in the reverse direction.
40

3. In a presser-foot mechanism for sewing machines, a head-frame, a work support adjacent thereto, a lever member pivoted on said head-frame, said lever member having a forwardly extending work-clamping portion in cooperative relation to said work support and a rearward sector extension 45 provided with two oppositely disposed sets of teeth, a second lever member pivoted on said head-frame with its axis coincident with that of said first-mentioned lever member, means for actuating said second-mentioned lever member to a neutral position and to positions on opposite sides of the neutral position, a pair of oppositely-disposed pawls on said second-mentioned lever member respectively arranged and adapted to engage one of the sets of teeth on the sector extension of said first-mentioned lever member when said second-mentioned lever member is moved from the neutral position, an arcuate guide-way on said head-frame, the radius of which is struck from the axis 50 of said lever members, a pair of oppositely-disposed cam members mounted adjustably in said guide-way, and means on said pawls coöoperating with the respective cam members whereby both of the pawls are held out of engagement with the sector extension of said first-mentioned lever member when the latter is in the neutral position, and whereby, also, said pawls alternately engage said sector extension to move said first-mentioned lever member in the corresponding direction when said second-mentioned lever member is moved from neutral position.
